Primary Examiner — Susan Bennett Hattan*Assistant Examiner* — Brett Miller(74) Attorney, Agent, or Firm — Moyles IP, LLC(57) CLAIM

I claim the ornamental design for a personal protective enclosure, as shown and described.

DESCRIPTION

FIG. 1 depicts a perspective view of a personal protective enclosure;

FIG. 2 depicts a front view of the personal protective enclosure;

FIG. 3 is a back/rear view of the personal protective enclosure;

FIG. 4 is left side view of the personal protective enclosure;

FIG. 5 is right side view of the personal protective enclosure;

FIG. 6 is a top view of the personal protective enclosure; and,

FIG. 7 is a bottom view of the personal protective enclosure. The broken lines showing parts of the personal protective enclosure are for the purpose of illustrating portions of the personal protective enclosure that form no part of the claimed design.
